(Cl. D47—7)

FIG. 2.

FIG. 1.

To all whom it may concern:

Be it known that I, Guido Clauss, a citizen of the United States, residing in Elizabethtown, Lancaster County, Pennsylvania, have invented a new, original, and ornamental Design for a Stocking, of which the following is a specification, reference being had to the accompanying drawing forming a part thereof, in which:

I claim:

The ornamental design for a stocking, substantially as shown.
